UNITED STATES PATENT OFFICE.

CHARLES E. STRUCK, OF NEWARK, NEW JERSEY.

THILL-COUPING.

SPECIFICATION forming part of Letters Patent No. 299,696, dated June 3, 1884.

Application filed January 26, 1884. (No model.)

To all whom it may concern:

Be it known that I, CHARLES E. STRUCK, of Newark, in the county of Essex and State of New Jersey, have invented certain new and 5 useful Improvements in Thill-Couplings, of which the following is a full, clear, and exact description.

This invention consists of a thill-coupling wherein a key is employed arranged to enter 10 slots made in the clip and thill-iron for locking the same together.

Reference is to be had to the accompanying drawings, forming part of this specification, in which similar letters of reference indicate 15 corresponding parts in all the figures.

Figure 1 is a broken side elevation of my new and improved thill-coupling, showing the axle in section, the clip being broken away on the line *x x* of Fig. 4. Fig. 2 is a sectional elevation taken on the line *y y* of Fig. 1. Fig. 3 is a side elevation of the clip partly broken away. Fig. 4 is a plan view of the clip partly broken away. Fig. 5 is a side elevation of the thill-iron head, and Fig. 6 is a perspective view of 25 the key.

A represents the clip, attached to the axle B by the shackle C; and D represents the thill-iron, secured to the thill F by the bolt F' in the ordinary manner. The clip A is formed with 30 the cheek-pieces *a a'*, and with the studs *b*, for retaining the block H of rubber back of the thill-iron D, as shown in Fig. 1, to prevent rattling, and the cheeks *a a'* are each formed with the inwardly-projecting studs *c c*, which constitute the pivot-pin of the thill-coupling, and 35 the cheek *a* is slotted below the stud *c*, as shown at *d*, and has the V-shaped cavity *e* formed in it. The cheek *a'* has the aperture *f* formed in it, as shown in Figs. 2 and 3. The thill-iron D 40 has the slot *g* and V-shaped cavity *h* formed in it, which correspond in size and shape with the slot *d* and cavity *e* in the cheek-piece *a* of the clip A, and the slot *g* is of such size as to be adapted to fit over the pin *c* of the clip A, as 45 shown in Fig. 2.

E represents the key for locking the clip A and thill-iron D together. This key is formed with the V-shaped tongue *i* to correspond with the V-shaped grooves *e h*, and is of a size adapted 50 to pass through the slot *d* and to fit snugly in the slot *g* of the thill-iron D, as shown in Fig. 2.

The key E is also made concaved upon its inner edge, as shown at *j*, Fig. 6, to fit the surface of the pin *c*, and is formed at its outer edge with the loop *k*, by which it may be attached to the loop *l* of shackle C by the strap G, as shown in Fig. 1. The slot *g*, made in the thill-iron D, is inclined downward and slightly forward when the thills are in place and held in working position, while the slot *d* in clip A 60 is inclined downward, so that the slot *g* will stand in front of the slot *d*, as shown in dotted lines in Fig. 1, thus holding the key E between the cheeks *a a'* out of line with the slot *d*, thus preventing absolutely the key E from working 65 out.

In order to attach the thills F to the clip A, the iron D will first be placed in the clip upon the pin *c*. Then the thills F will be depressed or the axle B raised until the slot *g* of the thill-iron D coincides with the slot *d* of the clip A. The key E will then be forced through slot *d* into slot *g*, where it will be held from edgewise movement by the tongue *i* entering the cavity *h*. The thills will now be raised or the axle B lowered. This will cause the slot *g* to carry the key E in front of the slot *d*, so that all endwise movement of the key is prevented by the cheek-pieces *a a'*. For detaching the thills, the same will again be depressed or the axle 70 B raised to bring the slot *g* of the thill-iron D into line with the slot *d* in the cheek-piece *a'*, and then a pin will be inserted into the orifice *f* in the cheek-piece *a* and the key E driven out, which will permit the thill-iron D to be 75 lifted off from the pin *c* and entirely out of the clip A.

Constructed in the manner described, it will be seen that the coupling is very simple, strong, durable, and cheap, and that it is perfectly secure against accidental uncoupling, and that the thills may be easily attached to and detached from the vehicle.

Having thus described my invention, I claim as new and desire to secure by Letters Patent— 95
1. The combination of the clip A, formed with cheek-pieces *a a'* and pin *c*, the cheek-piece *a* being provided with an irregularly-shaped slot, with the thill-iron D, also provided with an open irregularly-shaped slot, and a key, E, 100 of irregular form, to correspond with the slots in the cheek-piece and thill-iron, whereby,

when the key is passed through the slot in the check-piece into the slotted thill-iron, the said iron will be securely hinged to the pin *c*, substantially as set forth.

5 2. The combination of the clip *A*, formed with pin *c* and check-pieces *a* *a'*, the former having an inclined grooved slot, *d*, and the latter having an aperture, *f*, with the thill-iron *D*, having an inclined grooved slot, *g*, the said slots inclining in opposite directions, and the tongued key *E*, constructed to be passed through the slot *d* into the slot *g* when said slots are in alignment, and to be forced therefrom by a suitable implement passed through the aperture *f*, substantially as set forth.

10 3. The combination of the thill and clip irons *A* *D*, slotted as described, with the key *E*, formed with a loop, *k*, whereby said key may be connected to the axle by a suitable strap, substantially as set forth.

4. The combination of a thill-iron, *D*, formed with an open slot, one of the walls of which has a transverse groove therein, with a key formed with a tongue on one of its sides to register with said groove, whereby, when the said key is inserted in the slot, the slot will be closed, and a central aperture formed in the said thill-iron between the upper end of the key and the upper end of the slot, substantially as set forth.

15 5. In a thill-coupling, the thill-iron *D*, formed with slot *g* and cavity *h*, in combination with the clip *A*, having slot *d* and cavity *e*, and the key *E*, having tongue *i*, substantially as and for the purposes set forth.

CHARLES E. STRUCK.
